UNITED STATES PATENT OFFICE

LYLE D. LEWIS, OF CORWIN CENTER, PENNSYLVANIA

GAIN MAKING DEVICE

Application filed August 2, 1929. Serial No. 383,115.

The device forming the subject matter of the invention is particularly advantageous in forming gains in poles for cross bars and in the specification the invention is so exemplified. With the present invention such gains are finished in one operation and preferably means is provided whereby the bit for drilling the hole for the cross arm screws is also included. Features and details of the invention will appear from the specification and claims.

A preferred embodiment of the invention is illustrated in the accompanying drawings as follows:—

- 15 Fig. 1 shows a plan view of the device.
- Fig. 2 a section on the line 2—2 in Fig. 1.
- Fig. 3 an end elevation.
- Fig. 4 a front elevation of the device.
- Fig. 5 is a section on the line 5—5 in Fig. 1.
- 20 1 marks the pole and 2 the frame of the gain cutting device. This is formed with end plates 3 and front and rear plates 4. The machine is braced by cross bars 5 at the upper front and rear corners.
- 25 A chain 6 is secured by a pin 7 to one of the side frames and extends diagonally around the log to the opposite corner of the frame where it is secured on a hook 8 formed on a sliding bar 9. The sliding bar 9 is carried in a guide pocket 10 formed in the corner of the frame. The bar has rack teeth 11 and a pinion 12 meshes with this rack. The pinion is fixed on a shaft 13. The shaft 13 has a squared end by means of which a crank 14 may be placed on the rod 13 for turning the pinion. A handle 15 is provided for the crank. This is carried by a pin 16 which extends through the crank. A spring 17 is tensioned against a shoulder 18 on the pin 16 and tends to force it inwardly. The pin is adapted to enter any one of a series of openings 19 in the side plate of the frame. When it is desired to tighten the chain, the chain is hooked on the slide 9 and is through the crank and pinion tightened and locked. By making the crank removable through the squared end of the pinion 13 it may be put in position so that at the point of tightening the handle is brought over the openings 19 so that the crank may be locked in tightened

position. The frame is provided with a series of teeth 20 which are adapted to engage the pole surface and assist in holding the frame in place.

A box-shaped guide 21 is arranged in the side of each side plate. Rollers 22 are arranged in these guides and trunnions 23 of a guide frame extend into the rollers 22, the box-shaped guide having an open slot 21a on its inner face to permit the entrance of the trunnions. Inner frame plates 24 extend from the guides 21 to the front and rear plates 4. Guide blocks 25 are carried by the trunnions 23 and these blocks are provided with openings 26, the openings 26 being extended through to the edge of the block by slots 27. Saws 28 are arranged in the slots 27 and have blade backings 29 which operate in the slots 26. The saw blades are connected by cross bars 30 and handles 31 are arranged on the cross bars for operating the saws. It will readily be observed that by reciprocating the saws the kerfs may be cut. The frame by the trunnions and blocks moves downwardly with the saws, the trunnions sliding down the slots 21a and the rollers 22 down the inside guides 21. The saws may be readily reciprocated and also are free to rock slightly as the frame may be left free to rock.

Chisel-shaped knives 32 are mounted on pins 33 extending from one saw blade to the other. They are provided with projections 34 which contact with the cross pins 35 forming a stop limiting the downward movement of the cutting ends of the knives. These knives are preferably staggered as clearly shown in Fig. 1, and are adapted to cut the bottom of the gain. As the saws are reciprocated cutting the end walls of the gain the knives or chisels remove the material between the saw kerfs so that as the saws complete their cut the gain is completed. A guide block 36 is carried by the trunnions. This has a centrally located opening 37 adapted to receive a bit 38 driven from a chuck or brace 39. One of the guide blocks 25 is provided with a socket 40 at its outer face from which extends an opening 41. A pin 42 extends through the opening 41 and the socket 40. The pin is provided with a shoulder 43

at the inner end of the socket 40 and a spring 44 is arranged between the bottom of the socket and the shoulder and tends to crowd the pin inwardly. The outer end of the pin 5 is provided with a cross pin 45 which is adapted to form a stop and lock the pin from being expelled by the spring. The pin has a knob at its outer end by which it may be manipulated. The inner end of the pin is adapted 10 to enter openings 47 in the inner side plates 24. There are a series of these openings adapted for different depths of the frame and the pin is intended to lock the frame in a position to bring the opening 37 perpendicular to the bottom of the gain. With the frame thus locked the hole for the cross arm screws is formed in the pole at the bottom of the gain, as clearly indicated in Fig. 2.

In operation, the frame is put in place, the 20 chain tightened. The saw and knives are reciprocated clearing out the gain. The frame is locked and the hole drilled and the frame removed with the gain complete and ready to receive the screw.

25 What I claim as new is:—

1. In a gain making device, the combination of a main frame; means for securing the frame to a pole; a guide frame; and reciprocating gain side and bottom forming cutters 30 carried by the guide frame.

2. In a gain making device, the combination of a main frame; means for securing the frame to a pole; a guide frame; and reciprocating cutters carried by the guide frame 35 comprising side saws adapted to cut the sides of a gain and flat knives adapted to finish the bottom of a gain.

3. In a gain making device, the combination of a main frame; means for securing the 40 main frame to a pole; a sliding and tilting guide frame having its axis positioned directly above the face of the cut; and reciprocating cutters carried by the guide frame.

4. In a gain making device, the combination of a main frame; means for securing the 45 main frame to a pole; a tilting and sliding guide frame; and reciprocating cutters carried by the guide frame, comprising side saws and intermediate knives.

50 5. In a gain making device, the combination of a main frame; a guide frame; and reciprocating cutters carried by the guide frame comprising side saws adapted to cut the sides of a gain and knives adapted to finish the bottom of a gain.

6. In a gain making device, the combination of a main frame; means for securing the frame to a pole comprising a tightening means and a lock to secure the means; a guide 60 frame; and reciprocating gain side and bottom forming cutters carried by the guide frame.

65 7. In a gain making device, the combination of a main frame; means for securing the main frame to a pole; an adjustable guide

frame in the main frame; reciprocating cutters carried by the guide frame; means locking the guide frame in adjusted position; and means for guiding a bit at right angles to the gain bottom on the guide frame.

70 In testimony whereof I have hereunto set my hand.

LYLE D. LEWIS.
